UNITED STATES PATENT OFFICE.

EMILE CABELLA, OF NEW YORK, N. Y.

GAUGE FOR PLATEN PRINTING PRESSES.

Application filed July 9, 1925, Serial No. 42,379. Renewed May 10, 1926.

The object of the present invention is to provide a gauge for the feed boards of platen printing presses, so designed as to include, as a unit, an adjustable tongue and being adapted for securing to the top sheet or tympan of the feed board by gluing supplemented by a paper strip, whereby the gauge, when secured in place, will have no tendency to cut the tympan and will insure perfect register of the sheets in the printing operation.

The invention will be understood by reference to the accompanying drawings, in which—

15 Figure 1 is a perspective view of a gauge constructed in accordance with the invention, secured upon the tympan of a press, and

20 Figure 2 is a plan view illustrating a make-up with the usual number of gauges in position.

Referring to the drawings, A indicates the tympan of a platen printing press and 1 my improved gauge. The gauge is rectangular in form and provided with broad flat 25 upper and lower faces. A suitable size for the gauge is $\frac{15}{16}$ " in length by $\frac{11}{16}$ " in width and a depth of $\frac{3}{16}$ ". But any desired size may be employed.

30 Extending through the gauge in a line substantially parallel with its upper and lower faces is a slot 2 and in this slot I place a guide tongue 3. Tongue 3 is bent upwardly toward its forward end, and may be bent downward at its rear end so as to provide a convenient means for moving the tongue endwise in the slot 2 for adjustment of its effective length.

35 In practice the depth of slot 2 may be appreciably greater than the thickness of the spring tongue so that the latter may be readily adjusted within the slot, a slight curvature from the front to the rear end of the tongue causing the latter to bear upon the walls of the slot with sufficient friction to hold the tongue in its adjusted position against ordinary stresses during the printing operation.

40 Inasmuch as the slot 2 is placed near one end of the gauge, an area is provided for the reception of a paper strip 4, one surface

thereof being coated with glue and the strip being glued to the top and side edges of the gauge and also to the tympan A. In practice the lower face of the gauge also will be 55 coated with glue and pressed upon the tympan sheet. By these two means, i. e. gluing of the gauge itself and the overset strip 4, the gauge is secured to the tympan sheet beyond any possibility of movement relative thereto in the printing operation, and the tympan sheet is not cut or perforated as in the case of the usual forms of gauges provided with tongues. Also the tympan sheet may be raised at any time without affecting the gauges secured thereon, to enable the placing of other sheets under the tympan sheet or the removal of sheets, in order to raise or lower the tympan relatively to the type face. 60

65 It is desirable that the gauges be so placed on the tympan sheet that the tongues in the case of an automatic feed press shall be nearest the side margins of the tympan, as in Figure 2, the position of the tongues 70 being reversed in the case of a hand feed press.

75 I have shown at a, Figure 1, slots additional to that shown at 2, and I reserve right to use as many slots as desirable so 80 that the tongue may be placed at various points relatively to the length of the gauge, as desired by the operator.

Having described my invention what I 85 claim and desire to secure by Letters Patent is as follows:—

A gauge for printing presses comprising a metal block, the said block being formed with an aperture extending through its side faces toward one end thereof, and a 90 gauge of metal movably held within said aperture, the said block being adapted for gluing directly upon a tympan and being adapted to receive supplementary securing means in the form of a narrow strip of 95 paper coated with glue for attachment to the block and to the tympan at one side of the tongue.

In testimony whereof, I have signed my name to this specification.

EMILE CABELLA.
